FLEXIBLE SEAT FOLDING CHAIR

Filed Jan. 22, 1929

UNITED STATES PATENT OFFICE

WALLACE G. GROSSMAN, OF WHITE PLAINS, NEW YORK

FLEXIBLE SEAT FOLDING CHAIR

Application filed January 22, 1929. Serial No. 334,170.

In flexible seat folding chairs, the seat commonly consists of suitable textile fabric such as canvas or carpet material. This invention relates more particularly to that part of the construction by which the front end of the flexible seat is secured to the frame of the chair.

A broad or general object of the invention is to provide an improved front construction. A more particular object of the invention is convenience in removing and replacing the flexible seat for its renewal. In this connection, other objects are durability, strength, comfort to the user, a handsome appearance, simplicity of construction, convenience of manufacture, and economy. Other objects and advantages of the invention will hereinafter appear.

The invention includes various features of construction and combinations of parts, as will appear from the following description.

In carrying out the invention, the front end portion of the flexible seat passes over a rather large rounded front bar and at its lateral edge margins passes over the rounded upper front ends of lateral leg members, the front edge margin of the seat being tapered in width to pass downwardly and rearwardly partially around the bar between the leg members. This tapered end of the seat is folded over upon itself to the inside and sewed down by a line of stitching, so as to leave a free flap and to provide a closed loop forming a passageway for a straight removable anchor rod the ends of which extend into holes through the leg members, this rod lying in a reinforcing groove in the adjacent side of the front bar. The flexible seat at its front end has no other connection excepting to its anchor rod, and this anchor rod has no other connection excepting at its ends with the leg members, so that thereby the front end of the flexible seat may be readily detached merely by pushing out the rod, and may be as readily replaced by a reverse operation.

One embodiment of the invention, which is illustrated in the accompanying drawings, will now be described and thereafter the invention will be pointed out in claims, refer-

ence now being had to the drawings, in which:

Fig. 1 is a perspective view of a flexible seat folding chair in which the invention is embodied;

Fig. 2 is an enlarged partial central vertical section from front to rear;

Fig. 3 is a section taken on the inclined line 3—3 of Fig. 2;

Fig. 4 is a partial rear elevation of the chair, and

Fig. 5, which is drawn to an intermediate scale, is an inverted plan view of the flattened out front end portion of the flexible seat per se, or as detached.

The illustrated embodiment of the invention will now be particularly described with reference to the accompanying drawings.

The frame of the folding chair shown in the drawings includes a pair of leg members 1 which in the unfolded condition of use of the chair shown incline downwardly and rearwardly from their upper front ends at an angle of about 45°. A large round upper front bar 2 is reduced and shouldered at its ends to form round tenons 3 which are mortised into the leg members 1. A rivet 4 passes through each of the leg members 1 and transversely through the tenon 3 so that thereby these leg members 1 and the front bar 2 are firmly and rigidly connected together. Obviously the tenons 3 may be further held in place by means of glue or other suitable adhesive if desired. The upper ends of the leg members 1 are circularly rounded flush with the circularly rounded surface of the front bar 2, so that the ends of these leg members form an outward continuation of the rounded surface of the bar 2.

On its lower and rear side in line with the leg members 1, the otherwise circularly rounded or cylindrical front bar 2 is provided longitudinally thereof throughout its length between the leg members 1 with a straight channel or groove 5 of uniform depth and width throughout. This channel or groove 5 is shown as of rectangular shape, but as will presently more clearly appear, it could as well be of a more or less different

contour or cross-sectional shape. A round hole 6 is provided through each of the leg members 1 in line with the groove 5 at its middle and outer portion, these holes 6 being of smaller cross-section or size than the groove 5. A straight rather rigid or stiff anchor rod 7 projects at its opposite ends into the respective holes 6. This rod 7 thus lies in the groove 5 throughout the length 10 of the latter, but this rod is free and is out of contact with or spaced from the bottom and side walls of the groove 5. The end portions of this rod 7 have a snug but removable drive fit in the holes 6 so that this 15 rod may be readily removed and as readily replaced from the outer side of either one of the leg members 1.

The chair has a flexible textile fabric seat 8, which in the particular folding chair 20 shown in the drawings is composed of carpet material of considerable thickness, as indicated in the drawings. The lateral edges of the seat 8 are shown as provided with a binding 9 which may be ordinary suitable 25 tape folded over the edges of the seat and stitched or sewed thereto as indicated, this binding 9 serving both to protect and to strengthen the edges of the seat 8.

Before the binding 9 is applied, both lateral edges of the seat 8 adjacent to its forward end are trimmed or cut to provide a tapering front end portion along the lines 10. The tapered front margin of the seat 8 is reversely folded over upon itself to the inside and at an intermediate point of this fold it is sewed to the adjacent portion of the seat 8 by a line of stitching 11 to form a terminal loop 12 which provides a flexible tubular passageway. This line of stitching 40 11 also provides a free reversely extending marginal end flap 13 which projects along the inner surface of the seat 8 from the line of stitching 11. Instead of the stitching 11, other suitable securing means might be employed, such for example as a row of clinched wire staples, although the stitched seam 11 has proved entirely satisfactory for the purpose.

The removable anchor rod 7 for the front 50 end of the seat 8 passes freely from end to end through the tubular passageway formed by the terminal loop 12, and it should be noted that the seat 8 as its forward end is connected only to this anchor rod 7, having 55 no connection to any other part, and that the anchor rod 7 is connected only to the leg members 1, without any connection to any other part. In order to provide a neat outer finish the outer end of each of the holes 6 is 60 covered by the large flat head of a small nail or tack 14 driven into the leg member 1, these large headed small nails being readily removed when it is desired to remove the seat holding rod 7.

65 By reason of the taper at 10 on the forward

end of the seat 8, the main portion of this seat which extends rearwardly from the top of the front bar or seat bar 2 will be of the full width of the front frame part of the chair from side to side between the outer 70 surfaces of the leg members 1, as shown in the drawings and as will be readily understood. Also the covering of the upper ends of these leg members by the side margins of the seat 8 not only provides a wider and a 75 more comfortable seat but gives a neater appearance, and at the same time the taper at 10 provides for the anchoring of the front end of the seat 8 to the anchor rod 7 between the inner surfaces of the leg members 1, as 80 above described. The large size of the front bar 2 of course adds to the strength of the framework of the chair. However, the large diameter of this round front bar 2, coupled with its carpet coverings 8, by reason of which 85 no part of this bar is visible, not only presents a handsome appearance but contributes largely to the comfort of the occupant of the chair.

The purpose of the groove 5 in the seat bar 2 is to reenforce the seat-holding anchor rod 7. When the stretched seat 8 is subjected to the weight of a rather heavy person, the rod 7 will spring slightly, whereupon the surrounding portion of the seat covering, 90 comprised in the folded over portion of its terminal loop 12, will be pressed along the middle portion of the rod, against the abrupt forward wall of the groove 5, so that thereby the rod 7 will be reenforced through the intermediary of this seat covering after only a very slight springing of the rod which is negligible for all practical purposes. Without this re-enforcing groove 5 and with a rod 7 of medium size such as shown, the weight of a 95 heavy person on the seat 8 might distort the shape of the seat uncomfortably and might even produce a permanent bend in the rod, by reason of which of course the distortion of the seat 8 would become permanent. Thus 100 the seat would be no longer smooth and even but would become sagged and wrinkled, thereby detracting from its appearance, as well as from the comfort of an occupant. It 105 should be obvious that by employing an anchor rod such as 7 of larger diameter, so that it would then be sufficiently stiff and rigid for holding the seat 8 even and taut throughout the length of the rod, such a rod 110 of larger size would not require any re-enforcement, and accordingly the groove 5 could be dispensed with, the outer surface of the rod then being located immediately adjacent to but slightly spaced from the adjacent 115 then unbroken outer surface of an ungrooved front bar otherwise similar to the front bar 2, as will be readily understood.

It should also be noted that when the weight of a person is applied to the seat 8, then the freely projecting flap 13 will be 120

pressed tightly against the lower surface of the round seat bar 2 immediately adjacent to the forward wall of the groove 5, which together with the abrupt corner formed by the groove itself and the extensive continuously rounded lower and forward surface of the bar 2 against which the seat 8 binds, will create a strong frictional resistance which will have a holding effect upon the seat and will 5 relieve the strain upon the anchor rod 7 to a considerable extent. In the same way and even to a further extent, the seam or line of stitching 11 is relieved from pulling strain thereon. However, it seems obvious that this 10 stitching 11 or some equivalent securing means could not be safely dispensed with altogether for holding the seat 8 with the weight of a person thereon. Furthermore, when the chair is folded, then the loop 12 formed by the stitching 11 prevents the end 15 of the loose seat from becoming disengaged from the anchor rod 7.

For detaching the front end of the flexible seat 8 from the chair frame when this seat 20 becomes sufficiently worn that it should be renewed, an ordinary punch or similar tool may be used for initiating the removal of the anchor rod 7, which after it has been thus started may be readily pulled out from its 25 outer end or pushed out from its inner end. It is unnecessary of course to pull this rod all of the way out, since it is obvious that after it has been moved endwise only enough to provide a convenient space between its 30 inner end and the leg member 1 from which its end has been removed, then the flexible seat 8, the terminal passageway or loop 12 of which is also flexible, may be readily slipped off over the free inner end of the rod 7. A 35 new seat 8 may be installed by reversing the operation, the inner end of the anchor rod 7 being pushed or driven from its outer end into the hole 6 in the leg member 1 from which it had previously been pushed or 40 punched out.

For conveniently performing this operation of replacing or renewing the flexible seat 8, the holding frame of the chair may be maintained in such a position that the flexible seat will be loose and easily manipulated, as will be readily understood. For example, and as will hereinafter more clearly appear, the seat 8 may extend away from the front bar 2, without being wound partly around this bar, as it is when the chair is in its unfolded condition of use, as is shown in 45 Figs. 1 to 4 inclusive.

The remaining parts and features of the complete practically operable folding chair illustrated in the drawings in which the present invention is shown as incorporated or embodied, are of a usual commercial construction, such as heretofore manufactured by me without the above described improvement which has been effected by the present

invention. In this connection it will be readily realized that this invention could be embodied in a chair which in other respects might be considerably varied or different in the construction of its general framework 50 from the chair shown in the drawings, it being only necessary of course that the chair as a whole should be so constructed as to cooperate effectively in a practical and workable manner with the present invention, substantially as hereinbefore described and as shown in the drawings. For a better understanding of the invention as carried out in a practical commercial folding chair construction, the remaining features of the chair shown in the 55 drawings will now be briefly described.

The lower rear end portions of the leg members 1 are firmly and rigidly connected together by means of a usual rung 15, thereby forming with these leg members and the 60 front bar 2 a rigid rectangular frame part. A pair of outer leg members 16 are arranged in a usual oppositely inclined X formation with the inner leg members 1. Each outer outer leg member 16 is pivotally connected 65 to the adjacent inner leg member 1 by means of a rivet 17, a washer (not shown) being interposed between these leg members to prevent their chafing by rubbing together and to provide a free pivotal movement. The 70 lower forward ends of the outer leg members 16 are substantially in vertical alignment with the forward edge of the seat 8 where it passes down and around at the front of the front bar 2. The lower portion of the leg members 1 and 16 below their pivot 17 are 75 made of the same length so that thereby the lower ends of the leg members 1 and 16 will come even with each other in their folded condition,—Fig. 1 of the drawings, by reason of its being a true perspective, being 80 somewhat deceptive in this respect.

The lateral edges of the horizontally stretched seat 8 pass immediately between and close to the inner surfaces of the inclined outer leg members 16, which extend for some distance upwardly and rearwardly beyond the rear end portion of the seat 8. A back frame has a main frame member 18 which is bent to the form of an inverted U, the straight 85 side bars of which extend at a slight inclination downwardly adjacent to the inner sides of and thence beyond the upper ends of the outer leg members 16. At the point where each of the side bars of this back frame 90 member 18 crosses the adjacent outer leg member 16, it is pivotally connected thereto by means of a rivet 19, with one or more interposed washers 20 (Fig. 4). A comfortable back rest 21 is provided at the top of the 95 bent frame piece 18 and at an intermediate point its side bars carry a back rest slat 22.

The lower ends of the side bars of the back frame member 18 carry a rear cross bar 23. This rear bar 23 is half round or semi-circu-

lar in cross-section with its rounded side at the front, providing a flat vertical surface at the back, and has its upper edge surface substantially in horizontal alignment with the rounded top surface of the front bar 2. The rear end portion of the seat 8 extends over the top of the rear bar 23 and the end margin of this seat bends over at a right angle and extends downward on the rear flat face of the bar 23 throughout the width of the latter, the end of this margin being flush or substantially so with the lower edge of the bar 23. It will be noted that this rear downwardly bent rear end margin of the seat 8 is of substantially the full width of the adjacent horizontal portion of the seat 8, the edges of which come close to the inner sides of the outer leg members 16.

The lower ends of the side bars of the back frame member 18 on their front side are notched slightly over and vertically across the full width of the rear vertical face of the cross bar 23 and at each side is rigidly and firmly secured to this cross bar by means of a rivet 24 which passes also through the interposed end margin of the seat 8, as indicated in Fig. 4. The ends of this rear cross bar 23 project beyond the outer sides of the back frame member 18 so as to abut against the inclined rear surfaces of the outer leg members 16, and the rear corners of these projecting ends of the bar 23 may be removed to provide a sloping or beveled surface and rounded ends, as shown in Fig. 4. The downturned rear end margin of the seat 8 is further firmly secured to the rear cross bar 23 by means of a rear clamping strip 25 and a series of screws 26 which pass forwardly through the clamping strip 25 and the interposed margin of the seat 8 and are screwed into the rear frame bar 23. The clamping strip 25 is of a length to fill the space between the inner sides of the notched lower ends of the side bars of the back member 18.

In effecting a renewal of the seat 8, the screws 26 together with the clamping strip 25 are of course readily removable. Also the end rivets 24 may be easily removed by any ordinary mechanic, as is well known. It is obvious, of course, that if so desired, bolts could be employed instead of rivets 24, but it has been found in practice that the rivets 24 provide a firmer and more rigid connection.

In the set up or unfolded condition of use of the chair as shown in Figs. 1 to 4 inclusive of the drawings, it will be noted that the flexible seat 8 will be maintained in a stretched condition between the top of the front bar 2 and the top of the rear bar 23, and at the same time the back frame, including its frame member 18, will be supported in an upright and slightly rearwardly inclined comfortable position, as shown in each instance in Figs. 1 and 2. The manner in which this chair may be folded into a sub-

stantially flat condition is so obvious from the drawings, as well known for this general type of folding chair, that it is believed to be entirely unnecessary either particularly to illustrate it or to describe it.

In effecting the removal of the flexible seat 8 for its renewal, this seat may be disconnected first at its front end from the anchor rod 7 as hereinbefore described, or it may be first disconnected at its rear end from the rear bar 23, as above described. In doing this, of course the chair may be placed in any convenient position both bodily and with reference to its pivoted frame. For example, if the front end of this seat 8 is to be disconnected first, then the pairs of pivoted leg members may be moved to a reversely crossed position, for thereby unwinding the seat 8 from around the front bar 2, as will be readily understood. On the other hand, should the rear end of the seat be disconnected first, then the seat may be unwound from around the front bar 2, so as then to hang loosely from the anchor rod 7, as will be clear from the drawings.

It is obvious that various modifications may be made in the folding chair construction shown in the drawings as an embodiment of the invention and above particularly described, within the principle and scope of the invention as defined in the appended claims.

I claim:

1. In a flexible seat folding chair, the combination of a pair of leg members having upper ends at the front of the chair, a rigid front seat bar permanently and firmly secured to the upper ends of these leg members and having therein a groove running along its lower side between the leg members, a straight rod free in the groove and removably supported at its ends in holes through the leg members, and a flexible seat having a closed loop which removably receives the rod and from which the seat passes upwardly around the front side of the seat bar and thence rearwardly.

2. In a flexible seat folding chair, the combination of a pair of leg members having upper ends at the front of the chair, a rigid front seat bar permanently and firmly secured to the upper ends of these leg members and having therein a groove running throughout its length along its lower side, a straight rod free in the groove and removably supported at its ends by the leg members, and a flexible seat having a closed loop which removably receives the rod and from which the seat passes upwardly around the front side of the seat bar and thence rearwardly.

In witness whereof, I hereunto subscribe my signature.

WALLACE G. GROSSMAN.
